CLAIM

The ornamental design for a pump enclosure, as shown and described.

DESCRIPTION

FIG. 1 is a front right top perspective view of a pump enclosure showing our new design;

FIG. 2 is a rear left top perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken lines shown in the figures represent portions of the pump enclosure that form no part of the claimed design.
